F. S. D. Edwin.

UNITED STATES PATENT OFFICE.

JOHN JAMES ROYLE, OF MANCHESTER, COUNTY OF LANCASTER, ENGLAND.

STEAM-TRAP.

SPECIFICATION forming part of Letters Patent No. 367,851, dated August 9, 1887.

Application filed July 30, 1886. Serial No. 209,559. (No model.) Patented in England December 30, 1882, No. 6,231; in France June 27, 1883, No. 156,269; in Belgium June 28, 1883, No. 61,861, and in Germany July 14, 1883, No. 25,315.

To all whom it may concern:

Be it known that I, JOHN JAMES ROYLE, a subject of the Queen of Great Britain and Ireland, and a resident of Manchester, in the county of Lancaster, England, have invented certain new and useful Improvements in Steam-Traps, (for which I have obtained Letters Patent in Great Britain and Ireland, No. 6,231, dated December 30, 1882; in France, No. 156,269, dated June 27, 1883; in Belgium, No. 61,861, dated June 28, 1883, and in Germany, No. 25,315, dated July 14, 1883,) of which the following is a specification.

This invention refers to the construction of that class of "steam-traps" which have a float working in the water of condensation to actuate the discharge-regulating valve. I employ a suitable valve located on the inlet of the trap and opening toward the atmosphere, so as to act also as a safety-valve; and I actuate the same by a simple float working in a reservoir or box, which is provided with a siphonic ejection pipe or outlet and a cover or lid, the latter adapted to retain a slight pressure of steam within the reservoir or box sufficient to eject the water through said pipe or outlet, as hereinafter more fully set forth.

It is necessary that the reservoir or box should be covered by a suitable lid. It is not necessary, however, that this lid be fastened down, as there is never more than a very slight pressure beneath it. A V-groove and gasket are most suitable, and the lid may be held on either by its own dead-weight or by one or more bolts. This construction of semi-open steam-trap possesses all the advantages of a closed trap, combined with the ready accessibility of what is known as the "open" construction.

Two sheets of drawings accompany this specification as part thereof.

Figure 1, Sheet 1, represents a vertical section of a steam-trap embodying the main features of my present invention. Figs. 2 and 3, Sheet 2, represent a preferred modification of the same invention, being respectively a vertical section and a plan view, the right-hand half of which is taken above the lid and its left-hand half below the lid.

Like letters of reference indicate corresponding parts of the respective traps.

In Fig. 1, *a* is an open-bottomed float working in a reservoir of water, *b*, provided with a pipe or outlet, *c*, passing through the bottom *d*, but rising to about the level of the water contained in the reservoir *b*. The top of the float *a* is connected to a lever, *e*, operating a hinged valve, *f*, which discharges into the reservoir *b*. This outer vessel or reservoir, *b*, is covered in by a suitable heavy lid, *g*, which, however, is not fastened down, as there is never more than a slight pressure under the cover, the necessary sealed joint being effected by the rim of the lid *g* dipping into a gasket containing V-groove *g'* at the top of the reservoir. 65

In Figs. 2 and 3, Sheet 2, *A* is the outer box or casing, preferably of cast-iron, provided with a cover, *B*, held on by wing-bolts *C*, and made tight in a gasket-groove, *C'*. This groove, like said groove *g'*, Fig. 1, is formed in the box and not in the lid, as heretofore, which prevents any water trickling down the box. Instead of the lid being held down by bolts, it may be weighted or held down by other means, the end to be attained being to retain a very slight pressure of steam under the said cover sufficient to eject the condensed water by the siphon-pipe *H*.

E is a hinged valve actuated by a lever and ball float, *F*.

L is an air-valve, heavy enough to close by its own dead-weight against any pressure that may be in the box *A* and held open by a brass expansion-bar, *M*, fastened at each extremity to the iron cover *B*, as shown.

The apparatus to be drained of air and water of condensation is connected by the union *O*, and the box *A* is filled with water to the level of the outlet *D* of the ejection-pipe *H*. The cover is then put on, and the apparatus is ready for action. The air-valve *L* is fully open owing to the expansion-bar *M* being cold and nearly straight, as illustrated. The ball-float is in the position shown by the dotted lines at *F* in Fig. 2, and the hinged valve *E* therefore 95 fully open. The air has consequently freedom of egress through the open air-valve *L* to the outer atmosphere, while the water of condensation is free to overflow through the pipe *H*, as indicated by the arrows. As soon, however, 100 as the steam arrives, the expansion of the brass bar *M* causes it to lengthen and bow downward,

and thus to allow the air-valve L to close onto its seating. This air-valve may be dispensed with in positions where there is no air to discharge, and it must be understood that its absence will not interfere with the action of the other parts of the trap. The closing of this air-valve causes the steam to accumulate under the cover B and eject the water from the box through the pipe H. The ball thus descends and partially closes the hinged valve E to diminish the supply of steam to the box. It will be obvious that this ejection action will cease as soon as the ball has so far closed the valve E that the amount of steam passing is absorbed by the natural condensation of the box. This valve E therefore never absolutely closes, and any condensed water collecting above the valve E would at first slowly pass the valve and add to the water in the box and raise the ball, thus opening the valve wider, and so on in a rapidly accelerating ratio until the steam again arrives, when all the water would be discharged through the pipe H and the valve E be closed, as before.

K is a small hole, formed in the division-plate N, which, when the trap is at rest, allows the water to run from the compartment I into J until it is level in both, so lifting the ball F and opening wide the valve E to about the position indicated by said dotted lines F² in Fig. 2, to allow of the utmost freedom of escape for air in the pipes on starting. By lifting off the cover B the ball and lever F can be thrown back, as indicated by dotted lines at F¹, Fig. 2, so opening wide the valve E for blowing out any dirt or obstruction which may have collected above the valve. This valve E and float F, arranged and acting as described, possess a special advantage over other descriptions of steam-traps, inasmuch as, besides performing their other functions, they operate as a safety-valve to prevent overpressure in the apparatus to which the steam-trap is connected. The escape of the water through the hole K goes on continuously; but its only object is to lift the float, and thus open the valve when the trap is at rest, as aforesaid.

The essential action of the steam-trap illustrated in Fig. 1 is the same as in the modification just described, the water being discharged and passing under the float a and over by the pipe c in the direction of the arrows, and so giving the same ejection action. The float and lever in this case, however, are counterbalanced by a spring, h, on an upwardly-extending rod, i, which rod also serves the purpose of lifting the valve, so as to permit the steam to blow through without removing the cover.

Instead of the valve E, Fig. 2, Sheet 2, and valve f, Fig. 1, Sheet 1, any well-known construction of plug-cock may be used, the action being substantially the same; or I may employ other forms of valves; but I have found the valves described very convenient in practice.

I am well aware that the employment of the description of float and hinged valve, illustrated in Figs. 2 and 3, Sheet 2, in steam-traps is not broadly new. They are similar, for example, to those used by John and William Weems in practically carrying out their invention the subject of British Letters Patent No. 734, dated March 17, 1862; but such ball and valve have always been used on the pressure side of the outlet and within a tightly-bolted vessel under the full steam-pressure, and not as herein employed on the atmospheric side of the inlet, whereby the valve is adapted to operate as a safety-valve, as aforesaid.

I am also aware that float-actuated valves for preventing overflow in liquid-reservoirs have been applied to the inlets of such reservoirs on the atmospheric side, but necessarily so as to be closed by the rise of the liquid and guarded against being opened by pressure, whereas my valve is opened by the rise of the water of condensation, and is also adapted to open under excessive pressure in the apparatus to which the trap is applied, as aforesaid.

Having thus described my said improvements in steam-traps, I claim as my invention and desire to patent under this specification—

1. In a steam-trap, a reservoir or box adapted to sustain a light pressure of steam within it, and provided with a float-actuated valve on the atmospheric side of its inlet and a siphonic ejection pipe on the pressure side of its outlet, substantially as herein specified.

2. In a steam-trap, a suitable float-actuated valve located on the atmospheric side of the inlet of the trap, whereby said valve is adapted to act as a safety-valve, as herein set forth.

3. A steam-trap having the water-space of its reservoir or box divided by a transverse partition, an inlet communicating with one compartment and a siphonic ejection pipe or outlet communicating with the other, said inlet being controlled by a float-valve the float of which works in said outlet-compartment, substantially as herein specified.

4. In a steam-trap having a siphonic ejection pipe or outlet, a transverse partition dividing the water-space of the reservoir or box into two compartments which communicate, respectively, with an inlet and with said outlet, and provided with a small hole near the bottom, said inlet being controlled by a float-valve the float of which works in said outlet-compartment, and said small hole permitting the water to find its level and thus rise in said outlet-compartment, when there is no steam-pressure, preparatory to the next beginning of the operation, substantially as herein specified.

In testimony whereof I affix my signature in presence of two witnesses.

JOHN JAMES ROYLE.
